UNITED STATES PATENT OFFICE.

HARRY B. WHITE, OF CANTON, OHIO.

ACCOUNT-CABINET.

1,032,457.

Specification of Letters Patent. Patented July 16, 1912.

Application filed July 10, 1907. Serial No. 383,032.

To all whom it may concern:

Be it known that I, HARRY B. WHITE, a citizen of the United States, residing at Canton, in the county of Stark and State of Ohio, have invented certain new and useful Improvements in Account-Cabinets, of which the following is a specification, reference being had therein to the accompanying drawings.

10. This invention relates to an account cabinet or file.

It is particularly adapted for the purpose of filing, in systematic manner, sales slips or account slips.

15. One object of my invention is to provide such a register or file of simple, compact construction and which is rapid in operation.

Another object is to provide a construction in which each individual cabinet or file 20. may be considered a unit or section, and any number of these units or sections may be readily connected together in simple manner, so as to present in appearance a file or cabinet of neat and uniform construction.

25. This last described feature is of importance to a merchant, as it enables him to add one section after another to his file, as his business justifies or demands.

Other objects of my invention will be understood from the description and disclosure 30. of a cabinet embodying it which I have herein chosen for the purpose of illustration.

Figure 1 is a front elevation of a cabinet embodying my invention. Fig. 2 is a section 35. on the line 2—2, Fig. 1. Fig. 3 is a perspective view of the cabinet-casing or housing. Fig. 4 is a perspective view of a trimming or facing strip to be interposed between two units or sections of a cabinet 40. embodying more than one unit or section.

Fig. 5 is a vertical transverse section illustrating the joint between two units or sections. Fig. 6 is a section on the line 6—6, Fig. 2. Fig. 7 is a section on the line 7—7, Fig. 2. Fig. 8 is a perspective view of a 45. series of trays removed from the cabinet casing. Fig. 9 is a perspective view of one of the trays, detached. Fig. 10 is a sectional detail view illustrating the method of 50. attaching the trays to the flexible hangers.

Fig. 11 is a perspective view of one side wall of the cabinet, detached. Fig. 12 is a perspective view illustrating a cabinet or file composed of several units or sections.

55. Fig. 13 is a perspective view of one of the

side frame members, detached. Fig. 14 is a perspective view of a modified form of tray.

In the drawings,—1 indicates as an entirety a suitable casing or housing. 2 is 60 a base or platform therefor. It is preferably made from a plate or sheet of metal having its edges turned down, as indicated at 2', so as to form a horizontally disposed platform or top 2^a for the base. Each unit 65 or section preferably consists of two tray-compartments arranged side by side within the casing or housing, although sections or units with but a single tray compartment may be constructed, if desired.

70. 3 represents as an entirety a framework for the housing and is carried by the base 2. Of this framework, 4, 4, represent side members or uprights, each of which is preferably made from a strip or bar of metal bent to 75. conform to the general contour of the casing. Each has an inclined front part 4', and is curved across its top as indicated at 4^a, and then carried vertically downward as at 4^b. The lower ends of these side members 80. are suitably secured to the top plate 2^a of the base 2.

5 is a cross bar or connecting member suitably secured at either end to the adjacent end members 4, 4, near the rear ends 85. of the top bars 4^a, 4^a, thereof.

6 is a member for dividing the casing into two compartments. This member 6 is arranged midway between the side frame members 4, 4, and is preferably formed of a bar or strip of metal having an inclined front leg 6' arranged parallel to the front inclined legs 4', 4', of the side frame members 4, 4, and a curved top 6^a arranged parallel to and conforming in shape with the curved top bars 4^a, 4^a of the said side frame members 4, 4. The rear end of the top part 6^a of this central member 6 is secured as indicated at 6^b to the cross bar 5.

7 is a facing strip extending along the inclined front portion 6' of the member 6, so as to give a neat appearance to the front of the cabinet by concealing behind it the edges of the trays at the center of the cabinet. The lower end of the division bar 6 is suitably secured to the platform 2^a, as indicated at 8.

9 is an inclined back or rest for the tray compartments. Preferably it is formed from a sheet of metal ribbed as indicated at 110.

9' both to form a division strip between the rear ends of the tray compartments and for the purpose of strengthening the said inclined back or rest. At either side the metal 5 forming the said inclined back or rest is flanged or bent rearwardly, as indicated at 9^a, for the purpose of strengthening the said back. At its lower end the back 9 is suitably secured, as indicated at 9^b, to the top 10 plate 2^a of the base. At its upper end it is suitably secured to the cross bar 5.

10 indicates as an entirety, a series of superposed trays. Each cabinet or file is provided with as many tray series as it has tray 15 compartments. The trays of each series are preferably supported from a pair of flexible hangers 11, 11, arranged at either side of the tray series. These hangers are preferably made of strips of fabric suited for the 20 purpose.

12 is a bottom plate for the tray series suitably connected at either side with the lower end of the adjacent flexible hanger 11.

13 is a top or supporting plate for the tray 25 series, suitably connected at either side to the adjacent upper end of one of the flexible hangers 11. For this purpose I have shown a rod 14 connected at one end to the top plate 13', as indicated at 14'. This rod extends along the under side of the top plate 13 from front to rear, a loop being formed in the adjacent end of the flexible hanger through which the said rod is passed. The rear end of the said rod is bent upwardly 30 through a hole 13' in the top plate and then again bent rearwardly as indicated at 14^a to secure it in position.

15 is a handle suitably connected to the top plate 13.

40 16 are rests for the rear ends of the top plates 13. Each of these rests is arranged against the inclined back 9 in either tray compartment, and may be suitably secured to the cross bar 5.

45 17 are rests or supports for the front ends of the top plates 13. Each of these rests 17 is suitably secured to one of the inclined standards 4', 4', 6', at the front of the casting or housing.

50 18 indicates a tray of which any desired number may be employed in superposed relation to form a tray series. Each tray 18 is preferably formed of a sheet of metal and has a bottom 18', an upward, rearwardly inclined back wall 18^a, a front wall 18^b, having a downward forward extending flange or plate 18^c with an upturned edge 18^d at its lower end. On the sides, the metal forming the tray, may be bent upwardly, as 55 indicated at 18^e. At either side near the center of the tray, the metal bottom of the tray is scored and the scored portion 18^f is turned downwardly, as indicated at 18^g, and then outwardly as shown at 18^h.

60 65 19 are flexible supports, each secured at

its upper end to the adjacent hanger 11 in any suitable manner, and having its lower end gripped or held between the bottom wall 18' of a tray and support-gripping part 18ⁱ struck from the said bottom wall of the tray. 70 Preferably the hangers 19 are made of fabric of suitable weight and strength.

The trays 18 are preferably arranged slightly inclined in series, with the inverted V-shaped front end portions of each tray 75 arranged to nest in the like part of the tray above it, so as to permit the independent movement of the front end of each tray relative to the trays above and below it in the series. This construction permits the collapsing of a tray series into a relatively 80 small space, which is advantageous for the purpose of storing it in a safe or vault, where economy of space occupied by a tray series is essential.

I have found it advantageous to turn the side edges of the metal forming the trays upwardly, as indicated at 18ⁱ, not only for the purpose of affording substantial side walls for the trays, but also to prevent the edges 90 of the trays from engaging the flexible supports 19 and cutting or otherwise mutilating them by wear and tear.

The inclined walls 18ⁱ of the trays may be serviceably employed to carry index cards. 95 With this object in view, at either end I have scored each of these walls, as indicated at 20, and then bent upwardly the portions of metal outside of each of said scored lines, as indicated at 20'. 21 indicates a suitable 100 index card, which at either end may be inserted beneath the adjacent raised part 20' of the wall 18ⁱ.

The introduction into and withdrawal of each tray section from its compartment will 105 be readily understood. The flexibility of each tray section as an entirety permits the bending and twisting of the section, so as to permit its easy introduction into or withdrawal from its respective compartment. 110 When in the compartment, in order to position the top plate of the section 13 in place, it is forced rearwardly over the rear support or rest 16 until its front edge clears the front rests or legs 17, 17 at either side thereof, when its front edge is elevated above said front supports and then moved slightly forward and rested upon them. To remove the top plate it is pressed rearwardly until its front edge clears the said front supports 115 17, 17, when it is permitted to drop downwardly at its front edge, and may then be removed with the tray series beneath it from the cabinet.

Where a flexibly connected tray series, 125 such as described, is used, I have found it advantageous to employ a bottom plate 12 at the lower end of the series for the lowermost tray to rest upon, as it preserves the alignment of the tray series and facilitates 130

the operation of the lower trays in each series.

While I have shown and described a tray series which is bodily removable from the casing or housing 1, it will be understood that I have done this simply for the purpose of illustration, and that my invention is not limited to such a construction. In some instances the proprietor may not care to use a collapsible tray series, and where such is the case, the trays of the series in the cabinet compartments may be tiltably supported in superposed relation to each other, in any suitable and well known manner, for example, as illustrated in the patent to Troutman No. 781,698, dated February 7th, 1905.

22, 22, indicate side walls for the casing. Each of these side walls is preferably formed of a sheet of metal having its front edge inclined and bent to form a groove at 22', and its rear edge bent to form a groove 22''. The groove 22' is shaped to receive an inclined front standard 4' of one of the side members 4, of the frame, and the groove 22'' is adapted to receive one of the rear vertical standards 4'' of a side member of the frame. These side plates 22 are placed in position by slipping each one down over its respective side frame member 4, and may be withdrawn by being pushed upwardly away from said frame member.

For the purpose of making a neat, compact cabinet and insuring the proper positioning of the lower ends of the removable side plates 22, I have secured along the sides of the top plate 2^a for each section or unit, a suitably grooved element 23, preferably formed of a strip of metal 24 bent at right angles to itself, as indicated at 24', then back upon itself, as indicated at 24'', then around to form a groove 24''. This groove 24'' is adapted to receive the lower end of the adjacent detachable side wall 22 and to properly position it and conceal it from view.

In order to present a comely appearance to the rear of the cabinet, which it is intended to expose to the customer, and at the same time to economically employ all of the space taken up by the cabinet, I have arranged to use the space in the rear of the inclined back 9 for the purpose of displaying articles of merchandise or for similar purposes. 25 indicates as an entirety a suitable window framework secured in position between the rear standards 4^b, 4^b, of the side frame members 4, 4. The said window frame rests at its lower end upon the top plate 2^a of the base, and at its upper end against the upper end of the inclined back 9. I prefer to use in the said window frame two vertically rising and falling window sashes 26, 26', the latter, which is the upper one, resting upon a stop 27 positioned at the upper end of the lower window 26.

28 is a shelf, bearing at its rear end upon a cross member 29, suitably secured in the framework, and at its front end upon a suitably positioned cross member 30. As many such shelves may be used as desired. It is understood that access to the interior of this display compartment is obtained by raising vertically upward either one or both of the sliding windows, 26, 26'.

Each unit or section of my account cabinet or file is adapted for ready attachment to or detachment from another similar unit. In order to add a unit to a cabinet, the detachable side wall 22 at one side of the cabinet is removed, and a facing element 31 is inserted between the side frame member 4 of the cabinet thus exposed and the side frame member 4 of the unit to be added, which is adjacent to it. This facing element consists preferably of a metal facing strip 32 bent to conform to the contour of the cabinet and inclosing and covering the adjacent side frame members 4, 4, of the two units or sections, which would otherwise be exposed. The contour of this facing strip may be maintained by suitable cross bars 33, connecting the front and rear uprights of the said facing strip. The units or sections may be secured to each other in any suitable manner. For this purpose I have shown bolts 34, a suitable number of which are extended through registering holes in the adjacent side frame members 4, 4, of the two units, 35 being nuts for the said bolts, used to bind the said side frame members of the units or sections together. In the manner just described, any desired number of units or sections may be connected together to present the comely appearance of a substantially integral structure. Whenever an additional unit or section is added to a cabinet, one additional facing element 31 is required to cover the connection between the side frame member of said added unit and the side frame member of the cabinet to which it is attached; but only two detachable side walls 22 are required, irrespective of the number of units or sections used.

In Fig. 14 I have shown a slight modification in the construction of the index card holder at the front of each individual tray. The inclined wall 18^c of the tray is scored, as indicated at 20^a, both vertically and horizontally, so as to form a tongue 20^b, which is depressed below the outer surface of said wall 18^c. The tongue serves as a resilient back for the index card holder. The card 21 is inserted between the resilient back or tongue and the front part of the wall 18^c at either end in front of it. The wall 18^c may be ribbed at either end as indicated at 20^c for the purpose of strengthening the card carrier.

The stiffening rib 9' for the back wall 130

may extend either forward or rearward therefrom, and may be formed either from the sheet of metal from which the said back is made, or of a separate piece of material riveted thereon, or attached thereto in any suitable manner.

While I prefer to use vertically rising and falling window sashes, as shown, if desired horizontally sliding or swinging doors, or 10 any suitable well known means may be employed for closing the display compartment.

What I claim is:—

1. In an account cabinet, the combination of a plurality of similarly shaped and 15 formed sections arranged side by side in a horizontal series, each section comprising a suitable base, side frame members supported upon said base at either side thereof, and a back arranged upon said base between said 20 side frame members and suitably connected at its upper end to said side frame members, a series of superposed trays arranged in front of said back and between said side frame members, and having their front ends 25 exposed at the front of said section, means connecting adjacent side frame members of adjoining sections together, and two side walls for the cabinet, arranged one at either 30 side thereof, one of said side walls being detachably connected to the outermost side frame member at one side of the cabinet.

2. In an account cabinet, the combination of a plurality of similarly shaped and formed sections arranged side by side in a 35 horizontal series, each section comprising a suitable base, side frame members supported upon said base at either side thereof, a back arranged upon said base between said side frame members, and means for supporting 40 the back between said side frame members, a series of superposed trays arranged in front of said back and between said side frame members, and having their front ends exposed at the front of said section, means 45 detachably connecting adjacent side frame members of adjoining sections together, and two side walls for the cabinet, arranged one at either side thereof, one of said side walls being detachably connected to the outermost 50 side frame member at one side of the cabinet.

3. In an account cabinet, the combination of a plurality of similarly shaped and formed sections arranged side by side in a 55 horizontal series, each section comprising a suitable base, side frame members supported upon said base at either side thereof, a back arranged upon said base between said side frame members, and means for supporting 60 the back between said side frame members, a series of superposed trays arranged in front of said back and between said side frame members, and having their front ends exposed at the front of said section, means 65 connecting adjacent side frame members of

adjoining sections together, and facing strips to conceal from view adjacent edges of side frame members of adjoining sections.

4. An account cabinet comprising a suitable base, side frame members supported upon said base at either side thereof, a back arranged upon said base between said side frame members, and means for supporting the back between said side frame members, detachable side walls, each slidably connected with one of said side frame members to permit its attachment thereto or detachment therefrom, the said side walls and back forming a tray compartment, and a series of superposed trays arranged in said tray 80 compartment.

5. In an account cabinet, the combination of a suitable base, side frame members secured to said base, each of said members comprising a bar of metal bent to conform 85 to the shape of the cabinet, a back supported in position by said side frame members, detachable side walls having slideable connection with said side frame members, and a series of superposed trays suitably mounted in a compartment formed by said side walls and back.

6. An account cabinet comprising a suitable base, side frame members supported at either side of said base and each formed of a bar of metal bent to conform to the desired shape of the cabinet, an inclined back supported upon said base between said side frame members and suitably connected with said side frame members, sheet metal side 100 walls, each connected with one of said side frame members and forming with said inclined back a tray compartment, and a series of superposed trays arranged in said tray compartment.

7. An account cabinet comprising a suitable base, side frame members supported at either side of said base and each formed of a bar of metal bent to conform to the desired shape of the cabinet, an inclined 110 back supported upon said base between said side frame members and suitably connected at its upper end with said side frame members, sheet metal side walls, each detachably connected with one of said side frame members and forming with said inclined back a tray compartment, and a series of superposed trays arranged in said tray compartment.

8. An account cabinet comprising a suitable base, side frame members supported at either side of said base and each formed of a bar of metal bent to conform to the desired shape of the cabinet, an inclined back supported upon said base between said side 120 frame members and suitably connected with said side frame members, sheet metal side walls, each having grooves to receive one of said side frame members, and forming with said inclined back a tray compartment, and 125

a series of superposed trays arranged in said tray compartment.

9. An account cabinet comprising a suitable base, a sheet metal back supported upon 5 said base and having a forwardly extending longitudinally and centrally disposed rib formed from the sheet of metal of which the back is made, frame members supported upon said base at either side of said back 10 and suitably connected with said back to hold the latter in position, a division member supported upon said base and arranged centrally between said side frame members and in front of the said rib on the back, and 15 two series of superposed trays, each series arranged in one of the compartments at either side of the division member.

10. In an account cabinet, a sheet metal tray having a bottom wall with portions 20 scored and bent thereunder, and supports for the tray, each attached thereto between the bottom wall and one of said turned-under portions of the bottom wall.

11. An account cabinet having a suitable 25 tray compartment with a back wall and standards at either side of the front of said compartment, a pair of flexible hangers, a top plate from which said flexible hangers are suspended, a series of superposed trays 30 arranged between and each suitably connected at either side to the adjacent one of said flexible hangers, a rest for the rear end of said top plate carried by the said back wall of the cabinet, and supporting lugs for 35 the front end of said top plate, each carried by one of said front standards.

12. An account cabinet comprising a suitable base, a sheet metal back supported upon 40 said base and having a longitudinally disposed sheet metal bracing rib arranged between its side edges, frame members sup-

ported upon said base at either side of said back and suitably connected to said back to hold the latter in position, and a series of superposed trays arranged to rest against 45 said inclined back.

13. In an account cabinet, a sheet metal tray having suitable bottom and front walls and a flange extending forwardly and downwardly from said front wall, the metal of 50 said flange being scored and the scored portion being bent rearwardly and then upwardly to form a resilient back to support an index card.

14. An account cabinet comprising a suitable base, side frame members supported at either side of said base and each formed of a bar of metal bent to conform to the desired shape of the cabinet, a back supported on said base, sheet metal side walls each 60 connected with one of said side frame members and forming with said back a tray compartment, and a series of superposed trays arranged in said tray compartment.

15. In an account cabinet the combination 65 of a base having integral depending side flanges adapted for connection to similar flanges of an adjoining base, side walls, a back mounted on the base, and means for supporting the side walls including angle 70 plates arranged along the opposite side edges of the base and each bent upon itself to form a longitudinally extending groove or recess to removably receive the lower edge 75 of one of said side walls.

In testimony whereof I affix my signature in presence of two witnesses.

HARRY B. WHITE.
